CLAIM

An ornamental design for a vehicle rear window, shown and described.

DESCRIPTION

FIG. 1 is a perspective view of a vehicle rear window;

FIG. 2 is front elevational view of the vehicle rear window (as seen from the rear of a vehicle);

FIG. 3 is left side elevational view of the vehicle rear window;

FIG. 4 is right side elevational view of the vehicle rear window;

FIG. 5 is a top plan view of the vehicle rear window;

FIG. 6 is a bottom plan view of the vehicle rear window; and,

FIG. 7 is rear elevational view of the vehicle rear window.

Any functional features of the vehicle rear window are not claimed.
